UNITED STATES PATENT OFFICE

WESLEY WAYNE HERBST, OF LIMA, OHIO

PRINTING PRESS PAPER GRIPPER

Application filed March 19, 1929. Serial No. 348,196.

The invention relates to a device, a spring and lever gripper, to be used on platen printing presses, which is so designed as to be easily and readily locked in the chase, at any position, along with the type form or within the furniture used in locking up the type form. The object is to afford a means of gripping the printed sheet firmly against the tympan sheet—at positions heretofore impossible with other style grippers—mainly for the purpose of preventing slurs and the slipping and blurring of the printed sheet.

One form of the invention is illustrated in the accompanying drawings. Figure I is the assembled view of the gripper; Figure II is the same, top view. Figure III is a cross-section view of the base before the lever is in place.

Figure IV is the lever, the moving part of the gripper, and Figure V is a cross-section view of the complete assembled gripper. Figure VI is a plan view of a chase including a sample type form, showing several of the grippers in operating position. Figure VII is a cross-section view of a platen printing press showing the relative positions of the grippers, chase, and type form in regard to the platen.

The base 1 constitutes the rigid framework of the device. In the lever 2 we have the moving part of the gripper, consisting of shaft 8 with end shaped to button 4, both of which are an extension of lever 2 which is rigid. The button 4 extends beyond the edge of base 1 allowing it (button) to strike tympan beyond printed sheet; also permitting the gripper to be locked within the type form itself as well as in the furniture surrounding the type.

The button 4 is somewhat above type-high which gives it the necessary leverage and allows it to strike the tympan in advance of the type form. The button is so called because it is shaped to the smallest practical, blunt point. This point will be inked while passing under the ink rollers but the extended shaft 8 embracing button 4 is so designed as to allow the dot to fall outside of the printed sheet whether the device is locked within the type form or in the lockup furniture.

On opposite end of lever 2 is spring or tongue 6 which grips paper, fastened to lever 2 by means of screws 7.7 permitting the interchanging of different length tongues. This spring 6 is flexible allowing it to bend and adjust itself while pressing against printed sheet. The normal position of spring 6 is down or in other words, less than type-high so as to prevent its inking while being passed over by the inking rollers.

The lever 2 is held in place within base 1 by rivet 3 which acts as pivot for lever 2. This lever 2 is placed in the base 1 somewhat off center, the end bearing the shaft 8 and button 4 being shorter than the end bearing the spring 6. This allows the spring 6 to be moved at a greater ratio than the shaft 8 thereby allowing the spring 6 to strike the printed sheet before the button 4 is compressed to its fullest degree. The end of lever 2 containing button 4 is supported and forced upward to its regular position when not being compressed in the process of printing by coil spring 5 which rests in groove 9 in the base 1.

Referring to Figures VI and VII. In Figure VI is shown a plan view of sample type form 10 which is locked within chase 11 through means of lockup furniture 12 and quoins 13. In this view it will be noted that the complete gripper 14 has been shown in several of its many operative positions.

The gripper 14, in five shown positions, is locked outside of the type form 10, in the furniture 12, and in one instance, within the type form 10. It is seen in each case that the spring 6 which acts as the gripper, falls within that part of the type form 10 coming in contact with the paper or in other words the spring 6 will fall on the sheet of paper being printed. Further, the button 4 on shaft 8 in each case falls outside the type form 10 and therefore outside the printing area, thus preventing the printed sheet being inked by the button 4. It will be clearly seen through this illustration that the gripper 14 may be placed at any position within the chase 11, said position being governed by the size and nature of the particular type form being printed.

Figure VII shows the chase 11 holding the type form 10 and grippers 14 in its regular position in the bed 15 of the platen press 16. In the process of printing the bed 15 comes in contact with the platen 17, and in so doing the button 4 of the gripper 14 strikes the platen 17 in advance of the type form 10 allowing spring 6 to press against the sheet of paper 18 preventing smear, sluff, and the possibility of slipping. In the counter-action, the coil spring 5 forces the shaft 8 back into position as button 4 leaves the draw sheet, thus lowering and preventing spring 6 coming in contact with rollers.

I am aware that various forms of grippers consisting of shafts and springs have been made prior to my invention. I therefore do not claim such a combination broadly, but, I claim:

1. A platen printing press paper gripper which may be locked at any position within the chase, along with the type form, the same consisting of lever and spring tongue, permitting the operation of the spring tongue without its being inked when passed over by the inking rollers.

2. A platen printing press paper gripper having a rigid lever, one end of which is shaped at end to button, said button being arranged to strike the tympan in advance of the type form, to thereby operate the device.

3. A platen printing press paper gripper having a rigid lever that is pivoted off-center in the base of the device, the spring end of which is longer than the button end permitting greater oscillation in the gripping spring.

4. A platen printing press paper gripper that may be locked within the type form, and the lever and shaft permitting the arm containing the button to fall outside of printing area.

5. A platen printing press paper gripper that may be locked outside the type form in the furniture, so the extended spring (adjustable as to length) will fall within the printing area, thus gripping the sheet.

6. A platen printing press paper gripper that is so designed that it may be locked within the chase and without interference, and adapted to be used in conjunction if necessary with other known style grippers now in use.

WESLEY WAYNE HERBST.
